UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, A CORPORATION OF MASSACHUSETTS.

CEILING-DRILLING MACHINE.

1,137,837.

Specification of Letters Patent.

Patented May 4, 1915.

Application filed November 16, 1914. Serial No. 872,332.

To all whom it may concern:

Be it known that I, HJALMAR G. CARLSON, a citizen of the United States, residing at Worcester, in the county of Worcester and 5 State of Massachusetts, have invented a new and useful Ceiling-Drilling Machine, of which the following is a specification.

This invention relates to a machine for use in buildings for the purpose of performing 10 drilling, tapping, and similar operations in the ceiling or in beams or other overhead work, and particularly for use in steel frame buildings.

The principal objects of the invention are 15 to provide a simple, strong and rigid construction whereby an electric motor can be supported from the floor, and a tool, as for example a drill, tap or the like, firmly mounted at the top of the machine, can be 20 moved up and down approximately to proper position and fixed in its adjusted positions; and means in connection therewith whereby the tool can be fed upward by hand, and still be connected with the motor 25 at all times during the adjustment. In this way the proper feed can be provided and the tool can be brought to proper position and yet it can be operated by the motor at the convenience of the operator.

Reference is to be had to the accompanying drawings in which, Figure 1 is a side elevation of a machine constructed in accordance with this invention with parts in 30 section; Fig. 2 is a front elevation of a part 35 of the machine showing it adjusted to a different position, and Fig. 3 is an enlarged sectional view on the line 3—3 of Fig. 1.

The machine is shown in a form comprising 40 a base plate 10 at the bottom on which it rests. Extending up from the center of this is a pipe 11 telescoping into the bottom of a pipe 12 above it. These two pipes are connected together in adjusted positions by a split collar 130 and a screw handle 13^a 45 which of course can be tightened to hold them in adjusted positions.

The top of the pipe 12 screws into the bottom of a frame 13 which has a vertical passage up through it. In this vertical passage 50 is a feed slide 14 which is provided with a rack 15. The frame 13 has ears 16 thereon provided with bearings for a horizontal shaft 17. This shaft has a pinion 18

meshing with the rack and is also provided with a ratchet wheel 19. A handle 20 is 55 pivoted to swing on the shaft 17 and is provided with a pawl 21 operated by a lever 22, whereby the handle can be operated to turn the shaft 17 and thus raise and lower the rack 15 and slide 14. The slide can be 60 fixed in its adjusted positions by means of a pivoted handle 23 which has a pawl engaging a ratchet wheel 24 fixed to the shaft 17 for holding the slide in its adjusted positions.

On the top of this slide is a gear casing 65 26. This is shown as formed in two parts secured together and inside the gear casing are two gears 27 and 28 meshing with each other. Through a square central hole in one 70 of these gears freely passes a square shaft 29 so that it will turn with it. This shaft will drive the gears in all adjusted positions. The shaft 29 constitutes the shaft of a motor 31, the casing of which is secured by bolts 75 or the like to ears 32 on the casing 13. Into the other gear passes a square shaft 30 which is fixed to the gear.

The slide 14 is provided with an upward projection 34 which is split and provided 80 with a screw handle 35 for tightening it in a well known way. Set down into a recess therein is a round hollow casing 36 in the form of a pipe which in this way is clamped to the slide 14 and moves with it. 85 In the upper end of this casing 36 is another circular hollow casing 38 secured by a split clamp 37. The clamp is designed to clamp these two casings together after adjustment.

At the top of the casing 38 is a head 39 90 fixed to it and provided with a ball rest for a set of bearing balls 40. Resting on the bearing balls is a cone 41 adapted to be tightened down in position by a collar 42 95 which has spanner holes, as indicated. This collar screws into the enlarged upper head 39.

Resting on the cone 41 is the tool-head 43 100 designed for receiving the drill 44, tap or other tool to be operated. At the bottom, this tool-head 43 has secured to it the upper end of a short interior solid square shaft 45. This shaft at its lower end is incased in and pinned to a hollow square shaft 46 105 which extends through the casing 38. The

top of the square shaft 30 telescopes into the hollow square shaft 46 so as to drive the latter in all of its positions.

It will be seen that the main frame 13 can be adjusted up and down by the telescoping of the pipes 11 and 12 and secured in its different adjusted positions. Furthermore, the two casings 36 and 38 can be adjusted so as to bring the tool into a position so that upon being fed upwardly by the handle 20 it will perform the desired operation in the ceiling or the like. During the feeding operation the gears 27 and 28 move up to continue to transmit power to the tool.

It has been found in practice that this machine saves a great deal of time in the drilling of holes of the character mentioned, and in performing other similar operations. It also furnishes a rigid construction and provides a firm bearing for the tool head at a point near the base of the tool.

Although I have illustrated and described a particular embodiment of the invention, I am aware of the fact that modifications can be made therein by any person skilled in the art without departing from the scope of the invention as expressed in the claims. Therefore, I do not wish to be limited to all the details of construction herein shown and described, but—

What I do claim is:—

1. In a tool of the character described, the combination of a frame, a shaft supported by said frame and extending upwardly therefrom, a telescoping casing movable with said frame and having means for carrying a tool head at the top, means for transmitting power to said shaft in all positions of the shaft, means in the casing for transmitting power to the tool head from the shaft in all positions of the casing, and means on the frame for raising and lowering the shaft.

2. In a tool of the character described, the combination of a base adapted to rest on the floor, a frame mounted on said base, a motor on the frame, a shaft supported by said frame and extending upwardly therefrom, a telescoping casing movable with said frame and having means for carrying a tool head at the top, means for transmitting power from the motor to said shaft in all positions of the shaft, means in the casing for transmitting power to the tool head from the shaft in all positions of the casing, and means on the frame for raising and lowering the shaft.

3. In a machine of the character described, the combination of a frame, a motor carried by the frame, a vertical shaft extending from the top of the motor, a slide carried by said frame and vertically movable therein, means on the frame for moving the slide up and down, a gear casing carried by said slide and movable therewith, two gears in

said casing meshing with each other, one of them turning with the motor shaft in all positions of the frame, and a tool shaft extending upwardly from said slide and fixed to the other gear to receive power therefrom. 70

4. In a machine of the character described, the combination of a frame, a motor carried thereby and having a vertical shaft at the top, a vertically movable slide carried by the frame, means for raising and lowering 75 said slide by hand, a pair of gears carried by said slide, one being connected with said motor shaft in all positions of the slide, a shaft connected with the other gear to transmit power therefrom and extending vertically from the top of the slide, a tool head mounted above the top of said shaft, and adjustable means for connecting said tool head and shaft to cause the tool head to be turned by the shaft. 80

5. In a machine of the character described, the combination of a frame, a motor carried thereby, a slide vertically movable on the frame, a square shaft extending upwardly from the top of said slide, means carried by said slide for connecting the motor shaft with said square shaft in all positions of the slide, a hollow cylindrical casing extending upwardly from the top of said slide and fixed thereto, a hollow cylindrical casing carried inside the first named casing and telescoping therewith, means for securing said casings in adjusted positions, a hollow square shaft inside the hollow cylindrical casings for receiving the first named square 95 shaft and transmitting power therefrom, and a tool head at the top having a square shaft entering said hollow shaft and receiving power therefrom. 90

6. In a machine of the character described, the combination of a frame, a motor carried thereby, a slide vertically movable on the frame, a square shaft extending upwardly from the top of said slide, means carried by said slide for connecting the motor with 100 said square shaft in all positions of the slide, a hollow casing extending upwardly from the top of said slide and fixed thereto, a hollow casing carried inside the first named casing and telescoping therein, means 115 for securing said casings in adjusted positions, a hollow square shaft inside the hollow casings for receiving the first named square shaft and transmitting power therefrom, and a tool head at the top having a 120 square shaft entering the top of said hollow shaft and receiving power therefrom, said tool head having a ball cone at the bottom thereof and said inner casing being provided with a head at the top thereof having 125 a ball rest, and a set of bearing balls therein for supporting the said cone and tool head.

7. In a machine of the character described, the combination of a frame, a slide vertically movable on the frame, a shaft extend- 130

- ing upwardly from said slide, a hollow casing extending upwardly from said slide, a hollow casing carried inside the first named casing and telescoping therein, means for 5 securing said casings in adjusted positions, means for receiving the shaft and transmitting power therefrom, and a tool head at the top having means for receiving power therefrom, said tool head having a ball 10 cone at the bottom thereof and said inner casing being provided with a head at the top thereof having a ball rest, and a set of bearing balls therein for supporting the said cone and tool head.
- 15 8. In a machine of the character described, the combination of a frame, a feed slide vertically movable thereon, a telescopically adjustable casing extending upwardly from the slide, a head on the top of said casing, 20 a tool head having a bearing in the first named head, and means extending up through the casing for rotating the tool head from below the casing in all adjusted positions thereof.
9. In a machine of the character described, 25 the combination of a frame, a slide vertically movable on the frame, a square shaft extending upwardly from the top of said slide, a hollow cylindrical casing extending upwardly from the top of said slide and 30 fixed thereto, a hollow cylindrical casing carried inside the first named casing and telescoping therewith, means for securing said casings in adjusted positions, a hollow square shaft inside the hollow cylindrical 35 casings for receiving the first named square shaft and transmitting power therefrom, and a tool head at the top having a square shaft entering said hollow shaft and receiving power therefrom. 40

In testimony whereof I have hereunto set my hand, in the presence of two subscribing witnesses.
